UNITED STATES PATENT OFFICE.

MARVIN D. BENNETT, OF SIDNEY, NEW YORK.

CAR-BUMPER.

1,291,373.

Specification of Letters Patent. Patented Jan. 14, 1919.

Application filed June 3, 1918. Serial No. 237,919.

To all whom it may concern:

Be it known that I, MARVIN D. BENNETT, a citizen of the United States, residing at Sidney, in the county of Delaware and State 5 of New York, have invented certain new and useful Improvements in Car-Bumpers, of which the following is a specification.

This invention relates to improvements in car stops and it is the principal object of 10 the invention to provide a spring bumper adapted for arrangement of a railroad track for stopping rolling stock in a manner to prevent injury to the same or the transmission of abnormal or excessive stress thereto 15 or to the bumper and track.

It is also an object of the invention to provide the bumper with novel means for supporting and securing the same in proper 20 relation to the track in a manner such as will prevent undue movement thereof.

The improvements in the details and arrangement of parts will be apparent from an inspection of the accompanying drawings, in connection with the specific description 25 hereinafter contained, and wherein the preferred embodiment of the invention is disclosed for the purpose of imparting a full understanding of the same.

In the drawings:

30 Figure 1 is a side elevation of the improved bumper as applied to a railroad track,

Fig. 2 is a top plan view thereof,

Fig. 3 is an end view of the same,

35 Fig. 4 is a fragmentary vertical longitudinal section through the bumper proper, and

Fig. 5 is a detail in section through the plunger showing the means for preventing 40 displacement thereof.

Having more particular reference to the drawings, in connection with which like reference characters will designate corresponding parts throughout the several views, *t* 45 represents the railroad track to which the improved bumper is attached. A transversely disposed bar or tie *b* is arranged over the track *t* and receives supports 1 thereon, said supports having apertured feet 50 through which connecting bolts 2 are passed into engagement with the bar *b*. As will be noted, the upper ends of the supports are shouldered as at 3 and are enlarged or widened as shown in the Fig. 1 whereby to 55 receive a casing 4, the lower portion of which

is shaped to permit the seating of the same on the shouldered ends 3 of the supports 1, whereupon it is secured in position by passing bolts 5 through the same and the adjacent portions of the supports 1. Diagonally 60 disposed apertured ears 6 are formed integral with the opposite sides of the housing 4 and receive the upper ends of connecting rods 7 therethrough, said ends of the rods being screw threaded and having nuts 8 turned 65 into engagement therewith while the lower ends of the same are bent at angles to the body portion thereof and extend downwardly through plates 9 into engagement with the cross tie *c* of the track *t*, said 70 plates 9 being formed with lateral extensions 9', the ends of which are disposed at substantially right angles thereto and apertured to permit the connecting of the same by bolts 10 to the web portions of the rails 75 of the track *t*. Obviously, by so connecting the casing of the bumper to the track *t*, movement of the same either longitudinally or transversely thereof, irrespective of the stress applied thereto will be prevented. 80

Slidably arranged in the casing 4 is a plunger 11, one end of which is enlarged as at 12 and snugly engaged in the bore of said casing while a head 13 is carried by said enlarged portion and as will be noted, serves 85 as the engaging means of the stop. The remaining end of the plunger 11 is extended beyond the casing 4 and is reduced to permit the passing of an annular locking plate 14 thereover, illustrated in the Fig. 5, said plate 90 having bearing on the adjacent end of the casing 4, which as will be noted, has the bore thereof reduced to permit the plunger 11 to be snugly passed therethrough. A coil spring 15 is arranged in the casing 4 about 95 the plunger 11, one end of the same bearing on the rear end of said casing while the remaining end of the same has engagement with the adjacent side of the enlarged portion 12. Hence, it is obvious that the head 100 13 will be normally maintained in its extended position with relation to the casing 4.

In using the improved bumper, it of course will be understood that the coupling head or other portion of the rolling stock 105 is engaged with the head 13, thus causing the same to be moved inwardly in the casing 4 against the tension of the spring 15, thus, cushioning the force of the impact and preventing the imparting of abnormal or ex- 110

cessive stress to the rolling stock or to the bumper and the track to which the same is secured.

By reason of the exceedingly simple construction of the improved bumper, it will be also understood that the various parts thereof can be readily removed for repairing or to permit replacing thereof, as may be necessary.

10 Manifestly, the construction shown is capable of considerable modification and such modification as is within the scope of my claims, I consider within the spirit of my invention.

15 I claim:—

1. A car bumper including a casing, a plunger slidable in said casing having one end thereof enlarged and snugly engaged in the bore of said casing, a head carried by the 20 enlarged end of the plunger, the remaining end of said plunger being extended beyond the adjacent end of the casing and recess, cushioning means arranged in the casing engaged with said plunger, and locking means 25 detachably engaged with the recessed end of the plunger arranged adjacent the outer face of the adjacent end of the casing.

2. A car bumper including a casing, a plunger slidable in the casing, having one 30 end thereof enlarged and snugly engaged in the bore of said casing, a head carried by the enlarged portion, the remaining end of the plunger being extended beyond the adjacent end of the casing, locking means engaged with said extended end of the plunger, cushioning means arranged in the casing engaged with the enlarged portion of the plunger, diagonal apertured ears formed 35 integral with the opposite sides of the plunger, and means receivable through said ears for securing the casing to a railroad track.

3. In a car bumper, in combination, supports, a casing having the lower portion thereof squared and connected to the upper 45 ends of said supports, diagonally disposed apertured ears formed integral with the opposite sides of said casing, rods received through said diagonal ears and extending downwardly into engagement with the ties 50 of a track, plates secured to the ties of a track and engaged with portions of said

rods, a plunger slidable in the casing, a head carried on one end of said plunger, a locking plate engaged with the remaining end of the plunger for preventing displacement 55 thereof, and cushioning means arranged about the plunger positioned in said casing.

4. In combination, a bumper including a casing, a plunger slidable therein, a head carried on one end of the plunger, the remaining end of said plunger being extended beyond the adjacent end of the housing, cushioning means arranged in the casing engaged with the plunger, locking means detachably engaged with the extended end of the plunger, longitudinally disposed base elements for the bumper, a tie disposed transversely of the base elements forwardly of the bumper, a second tie disposed transversely of the base elements and receiving 70 the bumper thereon, means for connecting the ties to the base elements, and tie rods engaged with said first tie and extending diagonally upward into engagement with said casing.

5. In combination, a bumper including a casing, supports receiving said casing, diagonally disposed apertured ears on the opposite sides of the casing, a plunger slidable in the casing having one end thereof enlarged 80 and snugly received in the bore of the casing, a head carried on the enlarged end of the plunger, the remaining end of said plunger being extended beyond the adjacent end of the casing, locking means engaged 85 with the extended end of said plunger, cushioning means arranged in the casing engaged with the enlarged end of the plunger, longitudinal base elements for the bumper, a tie disposed transversely of the base elements and arranged forwardly of the supports, a second tie disposed transversely of the base elements, means for connecting the ties to said base elements, and tie rods engaged at their lower ends with the first tie 90 and extending diagonally upward into engagement with the apertured ears on said casing.

In testimony whereof, I affix my signature hereto.

MARVIN D. BENNETT.
